Irma S. Ellicott and Eugene W. Silber,
West Orange, N. J.

Application August 30, 1944, Serial No. 115,137

Term of patent 7 years

(Cl. D34—5)

To all whom it may concern:

Be it known that we, Irma S. Ellicott and Eugene W. Silber, both citizens of the United States, residing at West Orange, in the county of Essex and State of New Jersey, have invented a new, original, and ornamental Design for a Game Board, of which the following is a specification, reference being had to the accompanying drawing, forming a part thereof.

In said drawing Fig. 1 is a plan view of a game board embodying our new design; and Fig. 2 is an edge elevation thereof.

We claim:

The ornamental design for a game board, as shown.

IRMA S. ELLICOTT.
EUGENE W. SILBER.
